UNITED STATES PATENT OFFICE.

FREDERIC KNICKEL, OF NEW YORK, N. Y., ASSIGNOR TO SPRINGMEYER, PATTBERG & CO., OF HOBOKEN, NEW JERSEY, A CORPORATION OF NEW JERSEY.

PURSE, HANDBAG, OR THE LIKE.

1,354,206.

Specification of Letters Patent. Patented Sept. 28, 1920.

Application filed April 21, 1920. Serial No. 375,645.

To all whom it may concern:

Be it known that I, FREDRICK NICKEL, a citizen of the United States, residing at 4441 Broadway, New York city, New York, have invented a new and useful Improvement 5 in Purses, Handbags, or the like, of which the following is a specification.

My invention relates to improvements in purses, hand bags or the like, and is more 10 particularly directed toward the provision of means to fasten the handle to the body of the purse, which means will be secure and effective, but which will not so injure the material of the bag either when it is manufactured or during use that it limits the useful 15 life of the bag.

In purses and hand bags heretofore in use, the weakest part of the article and the first to give away in use was the point at 20 which the handle was fastened to the bag.

I have found that these difficulties may be avoided by providing a handle fastening device which is adapted to envelop a comparatively large amount of material of 25 the hand bag or purse so that the load may be distributed.

In the drawings accompanying this specification and forming a part thereof, a preferable embodiment of my invention is set forth in detail for purposes of illustration. 30 In these drawings, Figure 1 represents a fastening device and a portion of a handle before the device has been fastened to the hand bag; Fig. 2 is a top plan view showing a handle fastened to the bag by the device shown in Fig. 1; Fig. 3 is a section on the line 3—3 of Fig. 2; and Fig. 4 is a view taken in the direction of the arrow 4 of Fig. 3.

40 The material of the hand bag, purse or the like, is shown at 5, and may comprise the usual materials such as fabrics, leather, imitation leather and the lining of the bag. The handle 6 is fastened to a link 7 in the usual fashion by fastening the end 8 to the body of the handle in any suitable fashion, as for example by stitching.

A sheet metal stamping A is bent to the form shown in Fig. 1. This stamping is 50 transversely bent approximately in the middle, as at 9, to provide two arms or members 10 and 11 substantially parallel with one another. The lower member 11 is provided with an aperture 12 near its free end, while

the upper member 10 is bent to form a 55 transverse open U 13 for the reception of the link 7, and with a projecting tongue 14 which may be a continuation of one of the sides of the U 13. The tongue is so located that it can coöperate with the aperture 12. 60 The material 5 of the hand bag, purse or the like is inserted between the parallel members 10 and 11 until the edge 15 of this material abuts closely the bent portion of the sheet metal stamping, the link 7 being 65 in place. Then the tongue 14 is forced through the fabric 5 and aperture 12 and bent down, as indicated at 16, thereby securely fastening the sheet metal stamping in place and providing a fastening device 70 for the flexible handle 6. It is contemplated, of course, that a similar member will be used at the other side of the hand bag, purse or the like for fastening the other end of the handle. As this member 75 will be identical with the one described, detailed description is believed to be unnecessary.

I have found that this device distributes the stresses in such a manner that the life 80 of the bag is considerably increased. It is, of course, apparent that all the material of the hand bag, which is inclosed by the sheet metal loop formed by the arms 10 and 11 bent at 9 and tongue 14, is rendered 85 active in sustaining the forces brought about in carrying the bag.

While I have described a preferable embodiment of my invention I would have it understood that the drawings are to be interpreted as illustrative of the invention rather than for limiting the same, as it is obvious that other structures might be used to accomplish substantially the same results.

What I claim is:

A handle fastening device for bags or the like, comprising a sheet metal member having an aperture near one end, an open transverse U at the other end, one side of the U being provided with a projecting tongue, 95 said sheet metal member being folded upon itself and inclosing a portion of the material of the hand bag or the like including the margin or edge thereof, the tongue passing through the material and aperture and 100 being bent over.
